UNITED STATES PATENT OFFICE.

AUSTIN F. JACKSON, OF TAUNTON, MASSACHUSETTS.

DESIGN FOR TEA AND COFFEE POT.

SPECIFICATION forming part of Design No. 21,291, dated January 12, 1892.

Application filed December 5, 1891. Serial No. 414,169. Term of patent 14 years.

To all whom it may concern:

Be it known that I, AUSTIN F. JACKSON, a citizen of the United States, residing at Taunton, in the county of Bristol and State of Massachusetts, have invented and produced a new and original Design for Tea and Coffee Pots, of which the following is a specification, reference being had to the accompanying drawings, showing a part thereof.

Figure 1 is a side view of the tea or coffee pot, and Fig. 2 is a plan view.

The leading feature of my design is the outer contour or shape of the body A. The bottom portion $a a' a'$ is of a somewhat globular shape, its lower half being an almost perfect hemisphere. The upper edge $a a$ of the lower half curves inwardly rather abruptly to a horizontal circumferential line $b b$, from which rises the upper half $b c$ of the body portion. This upper half is of smaller diameter than the lower half and curves first inwardly and then outwardly until it terminates in the flared upper edge $c c'$ of irregular outline. This irregular outline is composed of wave-like elevations c , with alternate depressions c' , there being two of the elevations c on each side. At the middle of each depression c' and extending down over the plain surface of the upper part of the body is a scrolled ornament d in relief.

Upon the larger lower half of the pot are arranged upon each side two sets of vertical flutes or corrugations $e e$, separated from each other a distance equal to one-fourth the circumference of the pot, and from the base of these sets of corrugations there extend the scrolled feet f , upon which the pot is supported. Upon the upper half of the body portion there are on each side two vertical creases or indentations g , which start or arise at the marginal elevations c and, extending downwardly, gradually die away before they reach the horizontal line $b b$.

In plan view the top of the pot has an outline of four quadrant scallops. The hinged cover B fitting thereon corresponds to this outline and has four corresponding creases or indentations h , between which are four raised

scroll ornaments, and from the center of which there arises a knob or finial i .

C is the handle of the pot. This has a broad end k , that joins the upper part of the body portion, and a broad lateral projection k' , that joins the lower half of the body portion. The handle proper rises at its upper end and increases in transverse dimensions and is provided at its extreme upper end with a scrolled ornamentation k^2 in relief, and thence descends and, decreasing in size, connects with the projection k' and, extending past the same, terminates in an outwardly-turned knob k^3 . Longitudinal creases or corrugations k^4 are formed in the middle portion of the handle and an ornamental raised work k^5 appears near the lower end.

D is the spout. This has a broad lower portion that connects with the lower half of the pot and tapers thence upwardly, and then at its extreme end turns outwardly. A scrolled ornament l is formed in relief upon the broad lower end of the spout, and just above this is a series of flutes l' , that gradually die away as they rise. A scrolled ornament l^2 in relief surrounds the end of the spout.

What I claim is—

1. The design for coffee and tea pots, substantially as shown and described.
2. In a design for a coffee or tea pot, as herein shown and described, the handle having the scrolled ornamentation k^2 , longitudinal creases or corrugations k^4 , ornamental raised work k^5 , and terminal knob k^3 , as shown.
3. In a design for a coffee or tea pot, as herein shown and described, the spout having upon the side of its broad lower end the scrolled ornament l in relief, and just above this a series of flutes l' , that die away as they rise, and a scrolled ornament l^2 in relief at the end of the spout, as shown.
4. In a design for a coffee or tea pot, as herein shown and described, the cover, as shown.

AUSTIN F. JACKSON.
